UNITED STATES PATENT OFFICE.

MOSES M. MARCUSE, OF NEW YORK, N. Y., ASSIGNOR TO WEST DISINFECTING COMPANY, OF NEW YORK, N. Y., A CORPORATION OF NEW YORK.

LIQUID-DISPENSING DEVICE.

1,116,717.

Specification of Letters Patent. Patented Nov. 10, 1914.

Original application filed January 7, 1911, Serial No. 601,447. Divided and this application filed June 24, 1911. Serial No. 635,178.

To all whom it may concern:

Be it known that I, MOSES M. MARCUSE, a citizen of the United States, and resident of the borough of Manhattan, in the city and State of New York, have invented a new and useful Improvement in Liquid-Dispensing Devices, of which the following is a specification.

This invention relates to certain improvements in the construction, form and arrangement of the several parts of a liquid dispensing device which is particularly well adapted for dispensing liquid soap or other liquid cleansing or antiseptic substance, into the hands of the person using the same.

The object of this invention is to provide means for locking the tilting liquid dispensing vessel to its supporting bracket when so desired.

In the accompanying drawings, Figure 1 is a front view of the liquid dispensing device, certain of the parts being shown in section, and Fig. 2 is a side view of the device, certain of the parts being shown in section, the liquid dispensing vessel being shown in an inverted position in dotted lines.

The bracket for supporting the liquid dispensing vessel comprises a post 1, its base 2 and head 3, from which head extend the bracket arms 4, 5. These bracket arms may occupy any desired angular position with respect to the post 1. In the present instance, the post is shown as extended horizontally from its support and the arms as depending vertically therefrom.

The liquid dispensing vessel is denoted by 6 and it may be made of any desired shape and material, preferably approximately globular and of glass. The upper continuous bead 7 and the lower interrupted bead 8 surround the vessel 6 between which beads is located the supporting band 9 which embraces the vessel 6. At the front of the vessel the band 9 is provided with a tilting handle 10. This band 9 is further provided at its sides with pivots 11, 12, which are located in suitable sockets in the ends of the

bracket arms 4, 5, for pivoting the vessel to said bracket.

The dispensing nozzle for the vessel is denoted by 13 and the discharge opening therethrough by 14.

Means are provided for locking the vessel against being tilted when so desired, which means comprises a screw 15 concealed in the head 3 of the bracket post, the point of which screw is arranged to enter the discharge opening 14 of the nozzle when the same is brought into alignment therewith. This screw 15 therefore serves both as a means for locking the tilting vessel against movement but also as a means for closing the discharge opening 14 of the nozzle. By concealing the screw 15 within the head of the bracket post, a special tool will be required for manipulating the screw and therefore the same is protected from being tampered with by unauthorized persons.

What I claim is:

1. A bracket, a liquid dispensing vessel pivoted thereto having a dispensing nozzle provided with a discharge opening and a screw carried by the bracket having its inner end arranged to be inserted into the discharge opening of the nozzle for sealing the opening and locking the vessel to the bracket against movement with respect thereto.

2. A bracket, a liquid dispensing vessel pivoted thereto having a dispensing nozzle provided with a discharge opening and a screw concealed in the bracket having its inner end arranged to be inserted into the discharge opening of the nozzle for sealing the opening and locking the vessel to the bracket against movement with respect thereto.

In testimony, that I claim the foregoing as my invention, I have signed my name in presence of two witnesses, this fifth day of June 1911.

MOSES M. MARCUSE.
